UNITED STATES PATENT OFFICE.

CHARLES O. ELLERT, OF BROOKLYN, NEW YORK.

METHOD OF AND APPARATUS FOR MAKING VENEERED CELLULAR CONCRETE WALLS.

1,280,427.

Specification of Letters Patent.

Patented Oct. 1, 1918.

Application filed March 10, 1914, Serial No. 823,808. Renewed April 10, 1918. Serial No. 227,825.

To all whom it may concern:

Be it known that I, CHARLES O. ELLERT, a citizen of the United States, and a resident of the city of New York, borough of Brooklyn, county of Kings, and State of New York, have invented new and useful Improvements in Methods of and Apparatus for Making Veneered Cellular Concrete Walls, of which the following is a specification.

10 This invention relates to a method of, and apparatus for improving integrally formed concrete walls.

A building wall made by the method of, and apparatus herein described has alternate cellular and pilastered sections throughout the wall and is of greater strength than "hollow" walls heretofore constructed; also provides a veneering or facing on both the outer and inner surface of the improved 20 cellular concrete wall; without in any manner detracting in strength and usage from that of an equal sized wall of solid reinforced concrete.

This invention will be understood by a 25 reference to the accompanying drawings forming a part of the specification, in which similar reference characters refer to similar parts throughout the several views.

Figure I, is an elevation showing a portion 30 of a veneered, cellular, pilastered, reinforced concrete building wall, and a mold as in relative operation; certain portions of the mold apparatus being removed to show a detail operation of the mold and the formation 35 of the veneered, cellular concrete wall.

Fig. II, is a cross section on line 2—2, Fig. I, parts of mold apparatus being removed, and parts broken away to show detail operative relation of the mold apparatus 40 and the formation of the veneered, cellular, pilastered concrete wall; the broken detail in side wall C, showing a preferred manner of securing mold panels, is better shown in Fig. III.

45 Fig. III, is an enlarged broken section of the cell forming means of the apparatus, and a portion of side wall C; parts being broken away, showing preferred manner of positioning and alining mold panels in 50 the building of the wall.

Fig. IV, is a perspective of a core holding means or core carrier forming part of the pilaster and cell forming means used in

connection with the formation of the cellular, pilastered concrete wall. 55

Fig. V, is a central vertical section of one of the chambered perforated cores.

Figs. VI, VII, a bottom and top perspective, respectively of a chambered, perforated core shown in Fig. V. 60

Fig. VIII, is a perspective of a closure or washer like means for closing the bottom chamber of a perforated core.

Fig. IX, is a perspective of a ring washer or like means positioned, preferably, intermediate the core and the adjacent core carrier, also as a means to distance cores from core carrier. 65

Fig. X, is a broken detail section, showing a modification of Fig. III. 70

Figs. XI, XII, XIII, are horizontal, broken sections through the veneered, cellular, pilastered concrete wall, showing modifications in construction, and showing variations in positioning the lining or veneering on both the outer and inner faces of the cellular, pilastered, re-inforced concrete wall. 75

A, indicates a veneered, cellular, pilastered, reinforced concrete building wall in the course of construction. B, indicates a suitable mold, which includes in its construction, the side walls C and D, suitably constructed, which are positioned and alined by a detachable, longitudinal wall gage member 8. 80

A preferred type of mold, is as shown, that will permit one of its side walls as C to collapsibly support a collapsible apparatus for forming cells and pilasters in a concrete wall, and which collapsible apparatus is integrally supported or carried within the mold and adjacent the inner face of said side wall of said mold. 85

The opposing side wall, as D, of such a mold is also preferably of a collapsible construction to permit the inner face of said side wall, as D, to be lined with a plurality of suitable facing elements, positioned in a manner to permit all joints or crevices caused by the meeting edges of adjoining sections of said facing elements, to be coated or sealed by a coating or sealing and bonding material or layer L of plastic or like, applied to the rear faces of said facing elements, to form said plurality of facing elements into one continuous and impervious 95 100 105

lining or veneering for the said concrete wall.

The said sealing and bonding material or layer L, of plastic or like is applied to the 5 facing elements, previous to the erection of side wall C to a height corresponding to that of the side wall D.

The sealing and bonding material or layer L of plastic is adapted to become set 10 or hardened quite readily and not only readily seals, and closes all joints and crevices of the said facing elements, but also greatly assists in positioning said facing elements by firmly bonding the said plurality of facing elements on their rear faces, 15 into one continuous and impervious lining or veneering; and also this sealing and bonding material or layer L of plastic or like is applied to a suitable thickness and 20 adapted to become an integral part of the cellular, pilastered concrete wall.

The sealing and bonding material or layer L of plastic is preferably applied with a brush to the rear faces of said plurality of 25 facing elements until all joints and crevices are thoroughly sealed and bonded; easy and ready access to the rear faces of said facing elements being had because the opposing side wall, as C, is of a height relative to 30 said side wall D, to readily permit the attaining of a continuous integrally constructed lining or veneering, and impervious on its rear face to wet or liquid plastic or concrete.

35 By the herein described method of building veneered, cellular, concrete walls, one of the side walls of the mold, as D, is erected always to an advanced height beyond that of opposing side wall C. The plurality of 40 facing elements are readily positioned adjacent the inner face of said side wall D, and a sealing and bonding material or layer of plastic or like, is readily applied to the rear faces of said plurality of facing elements to form or construct a continuous and 45 impervious lining or veneering for said concrete walls. The outer faces of said plurality of facing elements, adjoining the inner face of said wall D, need not have a sealing and bonding material or layer applied 50 to close the outer joints or crevices, because the sealing and bonding L applied to the rear faces of said facing elements, is sufficient to prevent wet or liquid plastic from 55 penetrating or leaking through the sealed and bonded lining or veneering adjacent the inner face of said side wall of mold.

Any crevices or joints showing on the 60 outside of the facing or veneering, after removal of said side wall D, may be pointed by hand with a trowel or by other suitable means.

I have described a manner of constructing 65 homogeneous wall facing or veneering, in which a plurality of unconnected facing

elements are suitably positioned in a suitable manner adjacent the inner face of a side wall of a mold, and formed into an impervious integrally constructed lining or veneering, and at the same time providing a better 70 bonding engagement with wet plastic poured adjacent the said homogeneous wall facing by reason of the sealing and bonding material or layer positioned intermediate the said facing elements and the wet plastic 75 poured in the mold; in this manner not only are the individual facing elements carried or supported by the set and hardened sealing and bonding material or layer but a better bonding engagement with wet plastic is attained in forming a veneered, cellular concrete wall.

The horizontal broken sections through the veneered, cellular concrete wall shown in Figs. XII, XIII, are approximately on a 85 line of the horizontal meeting edges of the facing elements I. The sealing and bonding material or layer L being shown extending longitudinally intermediate the cellular concrete wall and the wall facing, completely 90 embedding the tile positioning means and presenting a continuous sheet of bonding surface to the wet plastic used to form the concrete wall. In Fig. II, for clearness of drawing the holding means J are shown 95 uncovered by the sealing and bonding material or layer, but as described, the sealing and bonding material or layer L is applied to a suitable thickness to form an impervious integral wall facing or veneering, and 100 said wall facing is in turn bonded to suitable plastic to form a veneered, cellular concrete wall.

While suitable forms of molds may be adapted to the purpose of constructing veneered, cellular concrete walls, I prefer a type of side wall of a mold suitable for positioning a lining or veneering adjacent its inner face, as shown at D, the standards 1, 110 are provided with aligned openings or slots 2, 3, and 4, and are each positioned and aligned, and detachably secured to a longitudinal wall gage member 8, in a manner so each standard is independently and removably secured, independent of any adjoining standard; superposed removable spacing members 9, having slots or perforations 10, 11^a, to register with co-acting slots or perforations in said standards, are positioned adjacent the inner faces of co-acting standards, and suitable mold boards or panels 12, 12^a, having holding means 14^a 115 in recesses 13^a at or near the ends of said mold boards or panels 12, 12^a, are placed adjacent a coacting superposed removable spacing member 9, 9^a, in a manner to permit said holding means 14^a, to register with said 120 registering slots or openings 11^a, in said co-acting removable spacing members 9, 9^a; removable fastening means preferably clamp- 125 130

ing bolts, 15, 15^a, are then entered and passed into the registering slots in standards and removable spacing members 9, 9^a, and engage with said holding means 14^a, in the mold 5 panels 12, 12^a.

The removal of the fastening means 15, 15^a, permits the removal of spacing members 9, 9^a, and mold panels 12, 12^a, and removing the fastening means 8^b, from the 10 wall gage member 8, together with the removal of tie rods 5, permits the removal of the standards 1, from the finished wall.

Suitable facing elements I, of slate, terra cotta, or other material, are detachably positioned adjacent the inner face of said side wall D, and removable threaded bolts or like means S having threaded ends R to engage with threaded nuts K, are passed through or between the said mold panels 20 12, 12^a, forming the side wall D, and between the edges of the facing elements, or through notches placed in the edges of said facing elements if desired, and engage with a suitable holding or anchoring means J, 25 of suitable longitudinal angle iron members having suitable holes or openings to receive the threaded ends R of the fastening means S, and of sufficient length to engage a number of the facing elements, adjacent the rear 30 faces of said facing elements I.

The said facing elements I, when positioned, present crevices or joints at the meeting edges of adjoining facing elements, and as described a sealing and bonding material or layer L, of plastic or like is applied 35 with a brush or any suitable means to the rear faces of said facing elements I, to a suitable thickness to seal and close all the said crevices and joints, and preferably embedding said holding means J, and bond 40 the said facing elements I, into one continuous sheet of impervious integral wall fac- ing or veneering for a concrete wall.

The said side wall C, opposing the said 45 side wall D, is preferably of a collapsible construction, similar to that of side wall D, and is provided with a collapsible apparatus or means to be carried or positioned adjacent the inner face of said side wall C, for forming cellular, concrete walls with suitable cells opening out through the inner face 50 of said cellular walls, similar to a honeycomb type of wall construction and for forming if desired, suitable pilastered sections, preferably intermediate and alternating 55 with the said cellular sections of said concrete walls; the said side walls C, is erected in diminished height to that of side wall D, except at the finish of construction 60 of the cellular, pilastered wall, when said side walls C and D are of equal height if desired.

As shown in Fig. I, A, indicates a veneered, cellular concrete wall; the cellular 65 sections of the wall although shown in sin-

gle vertical series, intermediate and alternating with the pilastered sections, may be constructed to suit the requirements of the building operation. As shown each of the lateral extending cells G, opens into a vertical or flue like recess F, in the inner face of the cellular wall.

Intermediate and alternating with the cellular sections of the wall, are reinforced pilasters E, provided with, if desired smaller 70 open cells G'; the inner lining or veneering H, is of suitable material and is preferably positioned and secured to suitable anchor means N, of suitable material embedded or secured in such of the smaller cells G', as 75 desired, leaving open those cells G', not used for this purpose. If desired, suitable anchoring means O, Fig. XI, may be suitably positioned in some of the larger lateral extending cells G, and the inner lining or 80 veneering H, suitably secured by suitable screws or nails H', with an intermediate moisture proof lining M, of suitable material, between the face of the wall and the inner lining or veneering H.

The inner lining or veneering H, is adapted to form a closure means, referring to Figs. XII and XIII, for closing the vertical recesses F, in the inner face of the cellular wall in a manner to provide a vertical 85 flue like means in the inner face of the cellular wall, and the cells G, in the cellular wall open into the said vertical flue like recesses F, in the inner face of the said wall.

The said open cells G, are adapted to extend laterally through the inner face of the cellular wall, though the body of the said wall, to a point in the interior of the wall near the outer surface thereof, to leave a sufficient thickness of solid concrete wall to 100 support the outer lining or veneering I, 105 as heretofore described.

The said collapsible apparatus or means, positioned adjacent the inner face of said side wall C, for forming cellular pilastered 110 concrete walls, comprises, preferably, removable adjustable longitudinal core carriers 18, provided with alined slotted openings; said openings or recesses are adapted to pass transversely through said core carriers 18, and have a larger opening or slot 19, in one face of said core carrier 18, than that of opening or slot 20, in opposite face of said core carrier; a suitable holding means 21, preferably, a slotted plate is secured within the larger slot or opening 19, and is adapted to rest on shoulders provided within said larger slot or opening 19; said slotted plate or holding means 21, is secured to said shoulders by suitable screws 120 22, or like means.

The slots or openings 21^a, of the slotted holding plate 21, opens into the smaller recess or opening 20, in the opposite face of said core carrier 18. The said core carriers 130

18, may be of suitable length and are preferably positioned vertically to and adjacent the inner face of said side wall C, by removable securing means preferably clamping bolts 31, engaging suitable points, preferably, at or near the top and bottom ends of said core carriers 18, and pass through the side wall C, notches being provided in side wall C, to receive said securing means 31, and secured by a suitable nut 32, or like means.

Removable cell forming cores of a suitable construction, are provided, and are positioned adjacent the inner face of a side wall 15 of a mold, intermediate the standards, or adjacent the mold panels, and are removably secured by suitable fastening means passing through said side wall and engaging said cores. I prefer cell forming cores 23, as 20 shown in Fig. V, provided with a chambered recess or opening 25, in the top end of said cores and a chambered recess or opening 26, in the bottom end of said cores, these chambered recesses or openings are connected by a longitudinal, perforation or tube 24, opening into each of said recesses or openings 25, and 26; a holding means 27, or a modified form of holding plate similar to that of 21, in the core carrier 18, is provided in the top end of said cores 23, and extending across the chambered recess 25, and over the said perforation or tube 24, to provide a slidable, adjustable engagement with a suitable removable securing means 31, passing 25 through or between the units or members comprising said side walls, if desired, suitable notches or like means may be provided in said side wall to receive said securing means 31. The said securing means 31, are 30 adapted to pass through the slotted plate 21, in core carriers 18, and engage said holding means 27, in the top end of said cores 23; a slotted holding plate similar to that of 21, in core carrier 18, may be used in place of 35 the said holding means 27, in cores 23, but it is desired that said holding means 27, or like means in the top end of cores 23, be arranged to protect the opening of the perforation or tube 24, provided in said cores 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 carriers 36, and engage with adjacent removable cores; said auxiliary core carriers 36, are adapted to be positioned intermediate and preferably, alternating with suitable 5 mold boards or panels 37. In this modification, the side wall of mold may be suitably constructed, and including the auxiliary core carriers 36, may be entirely dismantled and removed, leaving, if desired, the said cores 10 in the newly formed wall, for removal at a later time from the set concrete.

In Figs. XI, XII, and XIII, I show modifications in construction of veneered, cellular concrete walls, in Fig. XI, the laterally extending cells G, in vertical series are carried out and open through the inner face of the wall A, and flush with the pilastered sections E, and in Figs. XII, XIII, the laterally extending cells G, open into 20 the flue like recesses F, in the inner face of said wall A. The recesses F may be closed by the inner lining H to form isolated air passages, or may be connected by suitable air spaces or passages F', or in any 25 desired manner.

I have herein shown a method of, and apparatus for making veneered, cellular concrete walls, wherein are described improvements producing an improved "hol- 30 low" wall of a type suitable for dwellings.

While I have shown and described the preferred embodiment of my invention, it will be understood that I do not wish to be limited to the precise construction herein 35 set forth, since various changes in the form and minor details may be resorted to without departing from the principle of, or sacrificing any of the advantages of this invention.

40 Having thus described the invention, what I claim as new and desire to secure by Letters Patent is:—

1. A method of building veneered, concrete walls, which consists in setting up a 45 plurality of unconnected facing elements spaced from a mold element, applying a coat of plastic bonding material to the rear faces of said facing elements to form an integral, impervious veneer, and depositing plastic 50 concrete between said veneer and said mold element.

2. A method of building veneered, concrete walls, which consists in detachably securing a plurality of facing elements to one 55 inner face of a wall mold, applying a coat of plastic bonding material to the rear faces of said facing elements to form an integral, impervious veneer, and depositing plastic concrete between said veneer and the opposite mold face.

60 3. A method of building veneered, cellular concrete walls, which consists in setting up a plurality of unconnected facing elements spaced from a mold element, positioning a plurality of laterally extending

cores upon said mold element, applying a coat of plastic bonding material to the rear faces of said facing elements to form an integral, impervious veneer, and depositing plastic concrete between said veneer and 70 said mold element and around said cores.

4. A method of building veneered, cellular concrete walls, which consists in detachably securing a plurality of facing elements to one inner face of a wall mold, 75 applying a coat of plastic bonding material to the rear faces of said facing elements to form an integral, impervious veneer, positioning a plurality of laterally extending cores upon the opposite inner face of said mold, and depositing plastic concrete between 80 said veneer and said opposite mold face and around said cores.

5. A method of building veneered, cellular concrete walls, which consists in detachably securing a plurality of facing elements to one inner face of a wall mold, applying a coat of plastic bonding material to the rear faces of said facing elements to form an integral, impervious veneer, 85 positioning a plurality of laterally extending cores upon the opposite inner face of said mold, depositing plastic concrete between said veneer and said opposite mold face and around said cores, detaching said first 90 mold element from said facing elements, and withdrawing said second mold element and its attached cores from the wall.

6. A mold for veneered concrete walls, comprising spaced mold walls, means connecting said walls, one of said walls adapted to detachably engage an integral, impervious veneer, and cell forming means upon the opposing mold wall, said means including a plurality of elements adapted to pass 100 through said opposing mold wall and detachably engage a plurality of cylindrical cores to extend partly across the mold space.

7. A mold for veneered concrete walls, comprising spaced mold walls, means connecting said walls, one of said walls adapted to engage a detachable impervious veneer, and a plurality of cylindrical cores detachably clamped to the opposing mold wall 110 to extend partly across the mold space.

8. A mold for veneered concrete walls, comprising spaced mold walls, means connecting said walls, one of said walls adapted to engage a detachable impervious veneer, a plurality of removable securing means positioned upon and passing through spaced notches or openings provided to extend through or between mold panels positioned in the opposing mold wall, and a plurality of cylindrical cores engaging said securing 120 means and detachably clamped to the said opposing mold wall to extend partly across the mold space.

9. A mold for veneered concrete walls, comprising spaced mold walls, means con- 130

necting said walls, one of said walls adapted to engage a detachable integral, impervious veneer, the opposite mold wall provided with a plurality of spaced notches or openings adapted to pass through said opposite mold wall, and a cell forming means upon said opposite mold wall, said means including a plurality of elements adapted to pass through said spaced notches or openings and detachably engage a plurality of cylindrical cores to extend partly across the mold space.

10. A mold for veneered concrete walls, comprising spaced mold walls, means connecting said walls, one of said walls adapted to detachably engage an integral, impervious veneer, and a cell forming means upon the opposing mold wall, said means includ-

ing a plurality of elements adapted to pass through said opposing mold wall and detachably engage a plurality of core carriers to register within the mold space adjacent the inner face of said opposing mold wall, and a plurality of elements adapted to pass through said core carriers and detachably engage a plurality of cylindrical cores to register adjacent the exposed faces of said core carriers to extend partly across the mold space.

In testimony whereof, I have signed my name in the presence of two witnesses.

CHARLES O. ELLERT.

Witnesses:

HOWARD E. PETTIT,
JOSEPH HOYM.
